UNITED STATES PATENT OFFICE.

CHARLES S. NELSON, OF SANDPOINT, IDAHO, ASSIGNOR OF ONE-HALF TO MALVERN L. BRUCE, OF SANDPOINT, IDAHO.

PUNCTURING MACHINE.

Application filed November 23, 1925. Serial No. 70,969.

The present invention relates to improvements in puncturing machines which while especially designed for use in puncturing telegraph and telephone poles is also to be used with other work of similar nature. In the present exemplification of the machine the apparatus is adapted to puncture the exterior surface of a certain portion of a pole preparatory to a hot liquid bath of creosote or other preservative to be applied thereto for the prevention of decay. A predetermined area of the pole is pierced or punctured to an approximate depth of one-half to three-quarters of an inch, and the tools or spikes employed for this purpose are arranged so that they will enter the wood in such manner as not to break the fibers or grain of the wood. By this arrangement of the tools, although the pole is pierced, the penetration is with the grain of the wood and its structure is therefore not materially weakened by the treatment of the machine.

The apparatus of my invention involves the use of means whereby the pole may be adjusted longitudinally with relation to the puncturing tool, and vertically adjustable means are provided for shifting the weight of the pole preparatory to turning or partially rotating the pole as the work progresses. A power-operated mechanism is employed for this rotary feed of the work or pole and the latter is intermittently turned upon its longitudinal axis when the pole is elevated and its weight shifted. Means are also employed for retaining the elevated pole against lateral displacement as it is turned.

In co-operation with the feed mechanism I utilize a reciprocating carriage movable along the longitudinal axis of the pole and carrying a vertically reciprocable tool head and rotary tool for puncturing the pole. The rotary tool travels longitudinally of the pole and punctures the latter on the out-stroke or working stroke of the carriage and means are employed for rendering inoperative the vertically reciprocable tool head and tool on the instroke or idle stroke of the carriage.

At the end of the working stroke of the carriage and its tool the pole is elevated and then turned to present a new face for action thereon by the puncturing tool on its next outward or working stroke. In carry-

ing out these operations the invention consists in certain novel combinations and arrangements of parts aiding in the smooth-working, reliable, and efficient performance of the functions of the machine.

In the accompanying drawings I have illustrated one complete example of the physical embodiment of my invention wherein the parts are combined and arranged in accordance with one mode I have thus far devised for the practical application of the principles of my invention.

Figure 1 is a view in side elevation of a machine embodying my invention in operative position to puncture a pole.

Figure 2 is a transverse detail sectional view at line 2—2 of Figure 1 showing the means for elevating and partially turning the pole.

Figure 3 is an end elevation of the machine as seen from the right in Figure 1.

Figure 4 is an enlarged vertical sectional detail view of the rotary puncturing tool, its head and carriage and pressure connections or springs.

Figure 5 is a top plan view of the reciprocating carriage showing its operating mechanism, supports, and the puncturing tool.

Figure 6 is an enlarged side elevation of the reciprocating carriage and puncturing tool, together with the tracks for the carriage.

Figure 7 is an enlarged detail view at the rear end of the carriage showing the shifting mechanism for the carriage.

Figure 8 is a detailed view in side elevation, broken away for convenience of illustration, showing the rotary tool.

The main frame 1 is provided with a pair of spaced horizontal timbers or rails 2, 2, 95 having spaced concave rollers 3, journaled in bearings 4 and disposed transversely of the frame, and these concave rollers which form a supporting cradle for the pole P may be turned simultaneously by means of a power operated sprocket chain passing over sprocket wheels 5 on the ends of the roller shafts. The pole P is conveyed to its cradle in suitable manner and may be longitudinally adjusted to bring the desired area 100 into the zone of operation of the puncturing tools for puncturing the predetermined surface of the pole as it rests in its cradle.

The pole normally rests upon its cradle or concave rollers 3 during the working stroke 110

of the puncturing tool, but it is elevated, as in Figures 2 and 3, after each working stroke, in order that its weight may be shifted from the transversely disposed supporting rollers to longitudinally disposed rollers, and then the pole is partially turned during the idle stroke of the puncturing machine or tool. In this manner the pole is partially turned to successively present fresh faces to the puncturing tool. For this purpose I utilize pairs of spaced rollers 6, which as best seen in Figure 2 are disposed in the plane of the longitudinal axis of the pole, and these rollers may be elevated to receive the weight of the pole from the transverse cradle. These spaced pairs of rollers are disposed one at each side of the center of the pole and their shafts 7 are journaled in brackets 8. Each bracket has a lower threaded lug 9 through which is passed an oppositely threaded screw bar 10 having a hand wheel 11. These transverse screw bars are journaled in bearings of cross bars 12 supported on the main frame or timbers 2, and it will be apparent that by turning the hand wheels the brackets 8 and their pairs of rollers 6 may be moved laterally with relation to the pole. When the rollers 6 of a pair are drawn together by action of the handle wheel and screw bar the rollers frictionally engage under the pole at opposite sides of its center or longitudinal axis to elevate the pole from the supporting concave rollers 3. When the brackets and pairs of rollers carried thereby are moved outwardly or separated, the pole may be lowered to its cradle.

For turning the pole after it has been elevated I employ mechanism, operated from the overhead puncturing mechanism, including a pull or draw chain 13, having an anchoring hook 14 driven into the pole, and wrapped once around the pole at the start of the puncturing operation. The chain 13 is passed around and under the pole and then out to one side of the pole where it passes over a pulley or sprocket wheel 15 on the shaft 16, with the free end of the chain dangling. A control lever 13' and friction brake band or clutch band 14' are used in connection with the friction pulley 15' on the shaft as seen in Figures 1 and 2.

The shaft is journaled at 17 at the outer side of one of the sills 2 of the main frame and is power operated, intermittently, as will be described.

To retain the pole against lateral displacement as it is partially turned or rotated while in elevated position I use a retaining chain 18 which is passed around the pole adjacent to the turning chain 13, with its ends joined by a hook 19, and also passed around a guide sprocket wheel 20 on the shaft 16.

65 The puncturing mechanism is located

above the pole and the rotary puncturing tool operates on the top face of the pole while it is supported in horizontal position. For the support of the puncturing mechanism I utilize an upright frame 21 at one end of the machine which frame is provided with a pair of spaced, parallel, horizontal beams 22 projecting therefrom over the pole. An electric motor 23 is supported in the upper portion of the upright frame with its shaft 24 disposed transversely of the longitudinal axis of the pole. The motor shaft transmits motion to an upper gear shaft or countershaft 25 through the gear couple 26, and this gear shaft transmits rotary motion to the driving or operating shaft 27 through another gear couple 28, the latter shaft extending transversely of the two beams 22 and located above the beams.

The shaft 27 is instrumental in the intermittent turning operation of the pole and for this purpose is provided with an eccentric 30 which is connected by a downwardly extending link 31 to a ratchet mechanism 32 on the shaft 16 which is designed to operate 90 for turning the shaft 16 anti-clockwise and said shaft through the chain 13 turns the pole clockwise.

One end of the driving shaft 27 is provided with a crank wheel 33 and the pitman 95 34 pivoted thereon is pivotally connected to the reciprocating carriage 35 in order that the rotary motion of the shaft may be converted into reciprocating motion of the carriage. The carriage is provided with four 100 flanged wheels 36 which travel back and forth over the tracks 37 on the beams 22. On the working stroke of the puncturing mechanism the carriage moves outwardly or to the left in Figure 1 and on the in stroke 105 or idle stroke of the puncturing mechanism the carriage moves to the right in Figure 1. The rotary tool carried by the carriage rolls in a straight line over the pole on its working stroke to puncture the pole and the tool 110 is elevated from contact with the pole on its idle or instroke.

The rotary tool as seen in Figures 4 and 8 is made up of a suitable number of circular disks 38, spaced apart but rigidly secured 115 together by means of exterior retaining rings 39 and bolts passed through the rings and disks. Three sets of spikes as 40 are arranged at the periphery of the disks forming the rotary tool-carrier and these spikes 120 radiate from the carrier and are designed to penetrate the wood as the carrier rotates or revolves along the pole. Each spike is pivoted as at 41 between a pair of adjoining disks and a leaf spring 42 is connected at the 125 inner end of each spike. Movement of the spikes is limited by stop pins 43 carried transversely of the tool carrier and the springs which are anchored at 44 within the carrier permit a pivotal movement of the 130

spikes as the latter are withdrawn from the wood. This pivotal movement compensates for the forward rolling movement of the tool carrier and eliminates danger of tearing the wood fiber as the tool or spike is withdrawn therefrom. The spikes enter and are withdrawn from the wood in line with the grain thereof and therefore do not tear or cut the fiber of the wood which otherwise would be weakened by the incisions of the spikes.

Each of the disks of the tool carrier is provided with central hubs 45 journaled on the shaft 46 which is supported in the yoke 47 bolted at the lower end of a rack bar 48. This rack bar is vertically movable for adjustment in a vertically slidable tool head or housing 49, and a hand wheel 50, its shaft 51 and rack wheel 52 supported on the tool head may be used to vertically adjust the rack bar and tool with relation to the slideable or vertically reciprocable tool head or housing 49. When the proper adjustment of the rack bar is secured a clamp nut 53 is used to clamp and hold the rack bar rigid with the vertically reciprocable tool head in order that tool head and carrier are lowered during a working stroke of the rotary tool and elevated during the idle stroke of the rotary tool. The rotary tool is held in contact with the pole during a working stroke by pressure from a pair of springs 54 which bear upon a cross head 55 carried by and rigid with the vertically reciprocable tool head or housing 49. The springs are interposed between the cross head and flanged brackets 56 carried at the top of a frame or flanged support 57 rigid with the carriage. The tension of the springs and the pressure on the cross head and tool head may be varied to suit different conditions by turning the tension or adjusting bolts 58 of the brackets 56, which bolts operatively engage the upper ends of the

The tool head and rotary tool are pressed down during a working stroke and elevated against tension of the springs by mechanism actuated by the movement of the carriage during the return or idle stroke of the rotary tool and carriage, the tool head sliding in a central tubular guide 35' of the carriage as best seen in Figure 4.

At the opposite sides of the carriage or of the central tubular guide or casing 35' are disposed two horizontal lift bars 59 which are adapted to engage under and co-act with side lugs 60, bolted one at each side of the tool head and located above the central tubular guide of the carriage. These angular lugs project through side slots 61 in the frame 57 of the carriage, and of course guide the movement of the tool head as it is lifted by the action of the lift bars 59 and lowered when these bars are lowered to permit such

movement. The two lift bars are supported on the free ends of four crank arms 62 which are pivoted on the axles 63 of the carriage, and the supports for these free ends of the crank arms are cross bars or rods 64 and 65 at the respective front and rear ends of the carriage.

A spring 66 having one end attached to the frame 57 of the carriage and its other end connected to the front cross bar 64 tends to urge the lift bars up and hold them in engagement under the lugs 60 of the tool head.

At the front end of the track 37 a resilient bumper is provided for the carriage comprising a rigid frame 67 secured to the tracks in which are supported a pair of spaced bolts 68 and cross bar 69, with springs 70 interposed between the cross bar or bumper bar and the frame 67. Thus it will be seen that as the lifting frame (comprising the lift bars and crank arms as well as the cross rods) contacts with the bumper plate or bar 69, a cushioned movement is given to the bumper plate and the carriage is stopped and cushioned at the outer end of its working stroke. This impact of the lifting frame with the resiliently cushioned bumper also causes the lift bars to move backward with relation to the carriage, swinging the crank arms on their axles and thus causing the lift bars to swing upwardly, lifting the tool head through its lugs 60. The spring 66 also aids in this lifting movement and tends to uphold the lifting bars.

A pair of guard rails 71 are supported above the track rails 37 under which the grooved rollers of the carriage pass at the end of the working stroke of the carriage which aid in holding the carriage as the lifting movement is imparted to the tool head and rotary tool.

At the end of the idle or return stroke of the carriage the rear crank arms 62 of the carriage contact with a pair of stops 72 located in the path of movement of the carriage and fixed to the tracks 37. The contact with these stops of the crank arms throws the lifting frame forward and downwardly to release the uplifted tool head and rotary tools, and the two pressure springs 54 return the rotary tool to operative position for the next working stroke, which occurs after the pole has been partially turned beneath the tool.

At the forward end of the carriage a stop or abutment 72 is provided for the bar 64 to limit the rearwardly swinging movement of the lifting frame, and at the rear of the carriage a toggle locking device is carried to hold the lifting frame in elevated position.

This locking device comprises a pair of pivoted links forming a toggle 73 having one end anchored and pivoted at 74 on the carriage and its free end is pivoted at 75 to

an arm 76 of the crank arm 62. A guide rod or stem 77 is pivoted at the point 74 and has a loose sliding connection at 78 with the crank arm. As seen in Figure 7 when 5 the lift bars or the lifting frame are lowered the toggle is contracted and when the lift frame is elevated the toggle is extended as indicated by dotted lines to vertical position with the links of the toggle alined to 10 lock the lifting frame in elevated position. When the rear crank arms encounter the abutments 72 the toggle connection is opened to permit descent of the lifting bars 59.

The pole is thus intermittently given a 15 partial rotation after each working stroke of the rotary puncturing mechanism and the mechanism successively forms three parallel rows (of predetermined length) of incisions in the top face of the pole for the purpose 20 described.

Having thus fully described my invention, what I claim as new and desire to secure by Letters Patent is—

1. In a pole puncturing machine the combination with a supporting cradle, of pairs 25 of spaced longitudinally disposed elevating rollers and means for oppositely reciprocating said rollers, means for partially turning the elevated pole when supported on said 30 rollers, and means for restraining the pole against lateral displacement.

2. In a pole puncturing machine the combination with a supporting cradle, of means 35 for lifting and supporting the pole from said cradle, a turning chain operatively attached to the pole, means for drawing said chain to partially turn the pole, a retaining chain encircling the pole and a guide roller for said retaining chain.

3. In a pole puncturing machine the combination with a track, a reciprocating carriage and operating means therefor, of a 40 vertically reciprocable tool head, pressure springs interposed between said head and carriage for normally holding the head in

lowered position, a rotary tool carried by said head, actuating means on the carriage for elevating said tool head during an idle stroke of the carriage, and tappet devices for operating said actuating means. 50

4. The combination with a reciprocable carriage having a tubular guide casing, of a vertically slidable tool head in said casing, means for adjusting said head in relation to the casing and pressure springs bearing 55 upon said head, and means for elevating said head against the tension of said springs during an idle stroke of the carriage.

5. The combination with a reciprocable carriage having a guide casing, of a vertically slidable tool head and rotary tool carried thereby, pressure springs engaging said head to hold it in normally lowered position, elevating lugs attached to said head, and a tappet-operated pivoted-frame adapted to 65 coact with said lugs for elevating the tool head during an idle stroke of the carriage. 60

6. The combination with a reciprocable carriage, its guide casing, a slidable tool head in said casing, and pressure springs for 70 said head, of a tool bar adjustable in said head, a tool carrier on said bar, and puncturing-tools in said carrier.

7. The combination with a reciprocable carriage, its guide casing, a slidble tool 75 head in said casing, and pressure springs for said head, of a rack bar in said head, and a rack device for relatively adjusting said head and bar, a rotary tool carrier supported on said bar, and radially disposed 80 puncturing tools on said carrier.

8. In a puncturing machine the combination with a tool head of a tool bar, a rotary carrier supported on said bar comprising spaced rigidly connected disks, a series of 85 spikes pivoted in said carrier, and springs for retaining the spikes in operative position.

In testimony whereof I affix my signature.
CHARLES S. NELSON.
